US0D1015969S

(12) **United States Design Patent** (10) **Patent No.:** **US D1,015,969 S**
(45) **Date of Patent:** **** Feb. 27, 2024**

(54) **ANCHOR PIN FOR MOTORCYCLE
STEERING SPINDLE ASSEMBLY**

(71) Applicant: **Daniel J. McAllister**, Woodstock, GA
(US)

(72) Inventor: **Daniel J. McAllister**, Woodstock, GA
(US)

(**) Term: **15 Years**

(21) Appl. No.: **29/806,029**

(22) Filed: **Aug. 31, 2021**

(51) **LOC (14) Cl. 12-16**

(52) **U.S. Cl.**

USPC **D12/178**

(57) **CLAIM**

I claim the ornamental design for an anchor pin for a motorcycle steering spindle assembly, as shown.

DESCRIPTION

FIG. 1 is a top perspective view illustrating my design for an anchor pin for motorcycle steering spindle assembly.

FIG. 2 is a bottom perspective view thereof.

FIG. 3 is a front elevation view thereof, the rear elevation view, left-side elevation view, and right-elevation view being identical thereto.

FIG. 4 is a bottom view thereof; and,

FIG. 5 is a top view thereof.

1 Claim, 4 Drawing Sheets
